McKinley & Kirby Ltd.(57) **CLAIM**

The ornamental design for a music player, as shown and described.

DESCRIPTION

FIG. 1 is a perspective view of a music player of the present application;

FIG. 2 is a front view of the music player shown in FIG. 1; FIG. 3 is a side view of the music player shown in FIG. 1; FIG. 4 is a top view of the music player of FIG. 1; FIG. 5 is a perspective view of the music player, shown without the stand to show aspects of the design that are not visible when combined;

FIG. 6 is a side view thereof; and,

FIG. 7 is a bottom view thereof.

The broken lines depict portions of the music player that form no part of the claimed design.
